United States Patent Office

Des. 181,556
Patented Nov. 26, 1957

181,556

MOTEL

John J. Sullivan, Norfolk, Va.

Application October 11, 1956, Serial No. 43,334

Term of patent 14 years

(Cl. D13—1)

Fig. 1

Fig. 2

Fig. 3

Figure 1 is an elevational view of a motel embodying my new design.

Fig. 2 is an end elevational view of the motel of Fig. 1.

Fig. 3 is a top plan view of the motel of Figs. 1 and 2.

Fig. 4 is an enlarged fragmentary perspective view of the ramps shown in Figs. 1-3.

I claim:

The ornamental design for a motel, as shown.
